IGNITION BREAKER CONTACT DEVICE

Russell E. Phelon, West Springfield, Mass.

Application February 28, 1948, Serial No. 11,882

5 Claims. (Cl. 200—30)

1

The invention relates to an ignition contact breaker device particularly adapted for use in a high tension magneto.

One of the objects of the invention is to provide a breaker device of the type referred to having a leaf spring for biasing the breaker arm and having a simple and effective connection for the anchored end of the spring.

Another object of the invention is to provide a breaker of the type referred to having a leaf spring for biasing the breaker arm and having the spring so connected and arranged that it effectively serves to hold the breaker arm against forward movement.

Still another object of the invention is to provide a breaker device of the type referred to which is adapted for angular adjustment and which is constructed to facilitate such adjustment.

Still other objects of the invention will be apparent from the drawing and from the following specification and claims.

In the drawing I have shown in detail a preferred embodiment of the invention, but it will be understood that various changes may be made from the construction shown, and that the drawing is not to be construed as defining or limiting the scope of the invention, the claims forming a part of this specification being relied upon for that purpose.

In the drawing:

Fig. 1 is a combined front and sectional view of a high tension magneto provided with a breaker contact device embodying the invention.

Fig. 2 is a fragmentary sectional view taken along the line 2—2 of Fig. 1 and showing the breaker contact device.

Fig. 3 is a side view of the breaker contact device, the frame of the magneto being in section along the said line 2—2.

Fig. 4 is a plan view of the carrying plate of the device and of the parts rigidly connected therewith.

Fig. 5 is a side view of the parts shown in Fig. 4.

Fig. 6 is an exploded perspective view of the anchored end of the leaf spring and of the parts directly associated therewith.

Fig. 7 is a front view of the breaker arm and of the spring.

Fig. 8 is an enlarged front view of the upper portion of the parts shown in Fig. 7, this view showing the spring prior to the final forming thereof.

Fig. 9 is a view similar to Fig. 8 but showing

2

the spring in its final position with respect to the breaker arm.

Fig. 1 of the drawing shows a contact breaker device embodying the invention and also a high tension magneto with which the device may be used. The magneto as shown is the same as that set forth in my copending application for High Tension Magneto, Serial No. 676,413, filed June 13, 1946, now Patent 2,472,313, issued June 7, 1949. This particular type of magneto has been selected merely for purposes of illustration and the present invention is not in any way limited to a contact breaker device for use in combination with a magneto of this particular type.

The magneto as shown has a stationary frame or support 10 provided with a bearing for a rotatable shaft 12. Mounted on the frame or support 10 by means of screws 14, 14 is a core structure which comprises a magnetic core preferably laminated and shaped to provide three circularly spaced poles 16, 18 and 20 having arcuate faces which are concentric with the axis of the shaft 12 and equi-distant therefrom. The center pole 18 of the core is provided with a primary coil 22 and with a secondary coil 24. The primary coil 22 is suitably grounded as for instance by being connected with one of the screws 14. The ungrounded end of the primary coil is connected by means of an insulated conductor 26 with the breaker contact device to be described in detail. The secondary coil 24 is suitably grounded as for instance by being connected with the same screw 14 which is used for grounding the primary coil. The secondary coil is provided at its ungrounded end with an insulated conductor (not shown) which may be connected to the spark plug of an engine.

Carried by the rotatable shaft 12 and rotatable therewith is a field structure which includes an annular flange 28 of magnetic material, this flange surrounding the core structure which has been described. Secured to the inner face of the annular flange 28 are two permanent magnets 30 and 32 which are oppositely charged radially. The magnets 30 and 32 respectively carry pole pieces 34 and 36, the inner faces of which are concentric with the axis of the shaft and are so spaced therefrom as to be adapted to move in close proximity to the outer faces of the poles 16, 18 and 20 of the core structure. The said permanent magnets 30 and 32 cooperate with the annular flange 28 and with the pole pieces 34 and 36 to provide a magnetic circuit having inner pole faces of opposite polarity.

When the shaft 12 and the field structure carried thereby are rotated the magnetic flux in the central pole 18 of the core is suddenly reversed with a resultant high voltage in the primary coil 22. At the instant of maximum voltage, the electrical circuit through the primary coil 22 is broken by the breaker contact device, with a resultant high voltage in the secondary coil 24.

The breaker device to which the invention relates comprises a carrying plate 38 on which the other parts of the breaker device are mounted. Connected with the plate 38 is a pin 40 having a front pivot portion of uniform diameter. The pivot pin 40 has a portion of reduced diameter which extends through and fits an aperture in the plate 38, a portion of the pin being swaged over below the plate 38 to engage it and firmly hold the pin in place. A portion 42 of the pin 40 projects at the rear and fits a bearing aperture in the frame or support 10, the said portion 42 thus constituting a pivot about which the plate 38 and the parts carried thereby can be angularly adjusted. The plate 38 has two arcuate slots 44, 44 through which extend screws 46 and 48. The screws extend beyond the plate and enter threaded holes in the frame or support 10 and thus serve to hold the carrying plate in place and in face to face engagement with the said frame or support. A normally stationary contact 50 is supported on the carrying plate, an integral portion 52 of the said plate being bent forward to support the contact.

A rocker or breaker arm 54 is provided, this being formed of insulating material and being provided with a bearing aperture which receives and fits the pivot pin 40. One or more washers 56 are provided for separating the breaker arm 54 from the carrying plate 38. The breaker arm 54 carries a contact 58 which is movable into and out of engagement with the stationary contact 50. The breaker arm has an extension 60 which is engageable with a cam 62 on the shaft 12, the said cam cooperating with the extension 60 to rock the breaker arm. A leaf spring 64 is rigidly connected at its upper end with the breaker arm 54 and is electrically connected with the contact 58 thereon. The lower end of the spring 64 is anchored to the carrying plate 38 so that the spring serves to bias the breaker arm for movement in the clockwise direction, that is, in the direction to engage the contact 58 with the contact 50. The cam 62 moves the breaker arm in the opposite direction to overcome the bias of the spring and to separate the contact 58 from the contact 50.

The before-mentioned screw 46 is utilized to hold the lower or fixed end of the spring 64 and the said spring is provided with a loop 66 which surrounds or substantially surrounds the screw. Fig. 7 shows the spring 64 in its unflexed position, and it will be understood that upon assembly the spring is flexed from the position shown in Fig. 7 to the position shown in Fig. 1.

The spring 64 is insulated from the screw 46 and also from the carrying plate 38. As shown there is an insulating bushing 68 which surrounds the screw 46 and which is within the loop 66 of the spring. The said bushing preferably has an integral flange 70 at the top thereof. An insulating washer 72 is provided between the rear side of the spring loop and the front face of the carrying plate. It will be seen that when the screw 46 is tightened it serves not only to secure the carrying plate 38 to the frame but

also to clamp and firmly hold the looped end of the spring.

One or more electric terminals are electrically connected with the spring adjacent the looped end thereof and preferably there are two such terminals 74 and 76. As shown, the terminal 74 is connected with the aforesaid wire 26 and the terminal 76 is connected with a wire 78 connected with a condenser 80. The terminals 74 and 76 are preferably located at the front of the loop 66 of the spring and each of them has a flat portion which is apertured to receive the insulating bushing 68. Preferably a metallic washer 82 is provided between the head of the screw 46 and the flange 70 of the insulating bushing and a second metallic washer 84 is provided between the lower terminal 76 and the front edge of the spring loop. From the foregoing it will appear that when the screw 46 is tightened it not only secures the carrying plate and clamps the loop of the spring as already stated but it also presses the terminals 74 and 76 and the washer 84 against the said loop of the spring, thus insuring good electrical contact between the spring and the terminals.

Inasmuch as the front portion of the pin 40 is of uniform diameter throughout, the breaker arm 54 is free to move forward on the said pivot pin except as restrained by the spring 64. In order that the spring 64 may more effectively hold the breaker arm and prevent forward movement thereof, the upper face of the washer 72 is at such a level that when the screw 46 is tightened the spring is flexed rearward so as to bias or press the breaker arm in the rearward direction and thus effectively prevent any possible forward movement thereof. The upper face of the washer 72 is at a lower level than the upper face of the washers 56, this result being preferably attained by making the washer 72 somewhat thinner than the washers 56.

In order that the spring 64 may effectively serve as already described to hold the breaker arm against forward movement and to press it in the rearward direction, it is necessary that the upper end of the spring be very rigidly connected with the breaker arm so as to prevent any possible relative pivotal movement. Preferably and as shown the contact 58 is in the form of a head on a contact element 86 which extends through a portion of the breaker arm. The said contact element 86 extends through an aperture in the spring and the contact head 58 serves to hold the spring in engagement with the breaker arm.

In order to prevent relative pivotal movement about the contact element 86 the end portion of the spring extends beyond the end of the breaker arm and is reversely folded as indicated at 88. The end portion of the breaker arm is beveled as shown more clearly in Figs. 8 and 9. When the spring and the breaker arm are first assembled the looped or folded portion 88 of the spring is shaped approximately as shown in Fig. 8. Then the said looped or folded portion 88 is subjected to pressure so as to force it to the shape shown in Fig. 9. The edge of the spring is thus forcibly pressed against the beveled end of the breaker arm, so as to firmly hold the spring and arm in fixed relationship and so as to prevent any possible pivoting about the contact element 86.

It has already been stated that the carrier plate 38 is pivotally movable about the pivot pin extension 42. By angularly adjusting the carrier plate the extent of movement of the breaker arm

by the cam 62 can be varied. When the carrier plate is to be adjusted angularly the screws 46 and 48 are loosened and are again tightened after the adjustment has been made.

To facilitate adjustment the carrier plate preferably has a notch 90 therein and two pins 92, 92 are provided on the frame or support 10 immediately adjacent the notch. When the carrier plate is to be adjusted a suitable tool such as a screw driver can be inserted between the pins 92, 92 and into the notch 90. Then, with the screws 46 and 48 loosened, the carrier plate can be adjusted by moving the screw driver or other tool in one direction or the other as required.

What I claim is:

1. In an ignition breaker contact device, the combination of a carrying plate, a contact in fixed position on the plate, a breaker arm of insulating material pivoted for oscillatory movement about an axis perpendicular to the plate, a contact on the breaker arm movable into and out of engagement with the fixed contact, a headed screw extending through an aperture in the plate and adapted to enter a threaded hole in a support to secure the plate to the support, a leaf spring rigidly secured at one end to the breaker arm and having electrical connection with the contact thereon which spring has a loop at its other end at least partly surrounding the screw between the head thereof and the plate so that the looped end of the spring is clamped when the screw is tightened, the said spring serving to bias the breaker arm in the contact engaging direction, insulation between the looped end of the spring and the body of the said screw and between the said looped end and the plate, and an electric terminal electrically connected with the spring adjacent the looped end thereof.

2. In an ignition breaker contact device, the combination of a carrying plate, a contact in fixed position on the plate, a breaker arm of insulating material pivoted for oscillatory movement about an axis perpendicular to the plate, a contact on the breaker arm movable into and out of engagement with the fixed contact, a headed screw extending through an aperture in the plate, a leaf spring rigidly secured at one end to the breaker arm and having electrical connection with the contact thereon which spring has a loop at its other end at least partly surrounding the screw between the head thereof and the plate so that the looped end of the spring is clamped when the screw is tightened, the said spring serving to bias the breaker arm in the contact engaging direction, insulation between the looped end of the spring and the body of the said screw and between the said looped end and the plate and between the said looped end and the head of the said screw, and an electric terminal interposed between the last said insulation and the looped end of the spring, the said terminal being clamped against the outer edge of the said looped end of the spring to provide electrical connection with the said spring.

3. In an ignition breaker contact device, the combination of a carrying plate, a contact in fixed position on the plate, a breaker arm of insulating material pivoted for oscillatory movement about an axis perpendicular to the plate, a contact on the breaker arm movable into and out of engagement with the fixed contact, a headed screw extending through an aperture in the plate and projecting beyond the plate and adapted to enter a threaded hole in a support

to secure the plate in face to face engagement with the support, a leaf spring rigidly secured at one end to the breaker arm and having electrical connection with the contact thereon which spring has a loop at its other end at least partly surrounding the screw between the head thereof and the plate so that the looped end of the spring is clamped when the screw is tightened, the said spring serving to bias the breaker arm in the contact engaging direction, insulation between the looped end of the spring and the body of the screw and between the said looped end and the plate and between the said looped end and the head of the said screw, and an electric terminal interposed between the last said insulation and the looped end of the spring, the said terminal being clamped against the outer edge of the said looped end of the spring to provide electrical connection with the said spring.

20 4. In an ignition breaker contact device, the combination of a carrying plate, a contact in fixed position on the plate, a pivot pin fixed to the plate with its axis perpendicular thereto, the portion of the pin at the front of the plate being of uniform diameter, an oscillatory breaker arm of insulating material having a bearing aperture fitting the pivot pin, a contact on the breaker arm movable into and out of engagement with the fixed contact, a headed screw extending through an aperture in the plate, a leaf spring rigidly secured at one end to the breaker arm and having electrical connection with the contact thereon which spring has a loop at its other end at least partly surrounding the screw between the head thereof and the plate so that the looped end of the spring is clamped when the screw is tightened, the said spring serving to bias the breaker arm in the contact engaging direction, insulation between the looped end of the spring and the screw, insulation between the said looped end and the plate and having its upper face at such a level that upon tightening of the screw the spring is flexed rearward to press the breaker arm rearward, and an electrical terminal electrically connected with the spring adjacent the looped end thereof.

45 5. In an ignition breaker contact device, the combination of a carrying plate, a contact in fixed position on the plate, a pivot pin fixed to the plate with its axis perpendicular thereto, the portion of the pin at the front of the plate being of uniform diameter, an oscillatory breaker arm of insulating material having a bearing aperture fitting the pivot pin, a headed screw extending through an aperture in the plate, a contact element extending through a portion of the breaker arm and having a head constituting a contact movable into and out of engagement with the fixed contact, a leaf spring engaging at one end with the breaker arm and having an aperture through which the contact element extends so that the head of the said element holds the spring in place which spring has a reversely folded portion beyond the end of the breaker arm which is forcibly pressed against the said end of the said arm to prevent pivotal movement of the spring about the contact element, the said spring having a loop at its other end at least partly surrounding the screw between the head thereof and the plate so that the looped end of the spring is clamped when the screw is tightened and the said spring serving to bias the breaker arm in the contact engaging direction and also serving to prevent the said arm from moving forward along the pivot pin, insulation between the looped

end of the spring and the said screw and between the said looped end and the plate, and an electric terminal electrically connected with the spring adjacent the looped end thereof.
